UNITED STATES PATENT OFFICE.

EDWARD S. LEA, OF MORRISVILLE, PENNSYLVANIA, ASSIGNOR TO CARRIER ENGINEERING CORPORATION, OF NEWARK, NEW JERSEY, A CORPORATION OF NEW YORK.

APPARATUS FOR CASTING POTTERY WARE.

Application filed November 12, 1924. Serial No. 749,492.

To all whom it may concern:

Be it known that I, EDWARD S. LEA, a citizen of the United States, residing at Morrisville, in the county of Bucks and 5 State of Pennsylvania, have invented certain new and useful Improvements in Apparatus for Casting Pottery Ware; and I do hereby declare the following to be a full, clear, and exact description of the invention, such as will enable others skilled in the 10 art to which it appertains to make and use the same.

The invention relates to apparatus for casting pottery ware from slip, more particularly relatively flat pieces of large size, such, for example, as the tops of flush tanks, in which latter aspect the invention may be regarded as supplementary to the apparatus disclosed in a companion application, Serial 15 No. 749,491, filed of even date herewith, the present invention comprising a series of matched mold sections of porous material, preferably of standard form, permanently mounted upon a suitable support, preferably 20 a suspension truck, so that the component parts of the mold may be brought into accurate registry for the casting operations, and separated for the drying and conditioning operations, without separating the mold 25 parts from the truck and without dissociating the elements of the individual molds, in substantially the same manner as disclosed in the copending application aforesaid, the present apparatus involving certain novel 30 combinations and arrangements of parts to adapt it to the particular object in view, as will be more fully explained in the following specification, reference being made to the accompanying drawings, in which:—

40 Fig. 1 is a front elevation of a typical truck provided with eight tank cover molds, the mold parts of each set being shown in separated relation.

Fig. 2 is a side elevation of the same.

45 Fig. 3 is an enlarged plan view of the means for supporting and mounting the lower mold sections.

Fig. 4 is a fragmentary perspective view of two mold sections.

50 Fig. 5 is a perspective view, broken away in part to illustrate the mode of mounting the supporting shaft of the upper mold section in the latter.

Fig. 6 is a perspective view of a bracket attachment.

Although the particular apparatus illustrated in the drawings is equipped with a standard form of two part mold for the casting of covers of water closet flush tanks, from slip, it will be understood that the particular mold is only exemplary and that the apparatus is adapted to operate with molds for casting other forms of pottery ware, which molds include two mating sections, adapted to be brought into proper registry 65 and locked in such position during the casting and preliminary drying operations and separated and held in separated relation during the secondary drying of the casting, the 70 reconditioning of the mold parts and the 75 dumping of the casting.

Referring to the drawings, 1 indicates a generally rectangular frame, which may be conveniently constructed of channel bars with a central longitudinal bar 2, all of the 80 elements of the frame being connected together by electric welding. The rectangular frame constitutes the supporting truck for the mold elements and is supported from an overhead rail by suitably wheeled brackets 85 or trolleys 10, which may be of any standard or preferred form, to enable the truck to be moved from place to place in the factory or pottery, as the various operations incident to the fabrication of cast pottery ware 90 are carried out. Secured to the opposite sides of the truck frame 1 and to the intermediate bar 2 are two sets of laterally extending brackets 3, the brackets of each set being disposed in horizontal alignment and 95 the respective sets spaced apart vertically, to constitute journal bearings for the supports of eight lower or female mold sections 20. Each bracket 3 is provided at each of its outer ends with a generally U-shaped bearing 4 provided with oppositely disposed set screws 5—5, the purpose of which will be explained hereinafter.

Each lower mold section 20 is preferably 100 of the standard size and form employed in the casting of pottery ware of this particular type, the mold section being cast from plaster of Paris or other suitable porous material adapted to extract the water from the slip. As molds of this character 105 are quite fragile and liable to be damaged

by rough handling, special means for supporting each mold element 20 is provided, said means comprising two skeletonized cast metal end frames 8, which conform generally to the contour of the ends of the molds, each of said end frames being provided with angularly disposed flanges 11, which underlie the bottom of the mold section, the two frame members being firmly secured or clamped to the molds by tie rods 14 passing through ears 15 formed integral with the frames 8, as more particularly illustrated in Fig. 3. The central section of each frame is provided with a recess 9, in which is pivoted a cam hook 16, which latter serves as the means for locking the two mold sections together, as will be explained. Projecting laterally from the outer face of each frame member 8 is a journal pin or pindle 17, which engages the journal bearing 4 in the corresponding bracket 3, the journal 17 resting on the bottom of the bearing and being adjusted horizontally in the bearing by the set screws 5, this horizontal adjustment of the bearings of the lower molds being necessary to so position the lower mold section as to permit the upper mold section to register accurately therewith. In casting relatively flat or shallow hollow pottery ware of this general character, it is necessary that the mold be inclined slightly from the horizontal, so that the slip in the casting operation will run from the higher portion of the mold to the lower portion and completely fill the mold. In order to fix the inclination of the lower mold sections 20 with relation to the horizontal, the supporting frames 8 are each provided with lateral integral lugs 12, which engage the upper edges of the brackets 3 and hold the mold sections in proper position, as illustrated in Figs. 2 and 3. Said frames are also provided with lugs 13 near their forward edges, which are adapted to engage the lower edges of the brackets, when the lower mold sections are reversed in the dumping operation. The journals 17 are located forward of the longitudinal axis of each mold section 20, so that the predominance of the weight of the mold section and its supporting frame is toward the rear and normally holds the mold section in the position illustrated in Figs. 1 and 2 with the lugs 12 engaging the brackets 3.

55 The mating section 21 of each complete mold is, as indicated, of standard form and construction and is adapted to register with the section 20, so that the core portion of section 21 projects within the recess of section 20, as typically illustrated in Fig. 4, the space enclosed by the two sections defining the shape, size and configuration of the casting. Each of the upper mold sections or cores, as said sections are usually designated, 60 is provided with a longitudinal bore 25 through the body thereof to receive a shaft 24, the outer end of the bore being countersunk or recessed, as illustrated at 25' in Fig. 5, to prevent fracture of the material of the mold section due to bending or buckling of the supporting rod 24. Each of the upper mold sections 21 is pivotally supported by the rod or shaft 24 in a U-shaped frame 22, which, in turn, is pivotally mounted on a cross rod 23, which extends horizontally across the main frame 1 and is secured to the latter by suitable nuts. Two of these cross rods are provided, each supporting four of the frames 22 in which the individual upper mold sections are mounted. The shaft 24 of each upper mold section is located slightly to the rear of the longitudinal axis of the mold section, so that the latter tends to tip forward and downward in its supporting frame, but is normally restrained by an angular lug or detent 26 secured to the middle of the horizontal member of the frame 22. The mold member 21 is adjustable transversely in its supporting frame, the necessary adjustment being effected by means of collars 25 on the shaft 24, the said collars being locked to the shaft by set screws. The longitudinal adjustment of the upper mold member 21 in its supporting frame 22 and the fore and aft adjustment of the lower member 20 by means of the set screws 5 in the journal bearings 4, permit the relative adjustment of the two mold sections to cause the same to register accurately when they are brought together for the casting operation. The relation of the swinging frame 22 to the pivotal support of the lower mold section 20 is such that, when the frame and the upper mold section carried thereby is swung downward to the dotted position shown in the lower portion of Fig. 2, the upper mold section 21 will register accurately with the lower mold section before the frame 22 completes its downward movement, which latter is finally arrested by the lug or detent 26 engaging a recess 27 in the forward upper edge of the lower mold section 20.

Secured to the side members of the frame 1 are brackets 30, preferably formed of castings having the configuration shown in Fig. 6 with a central hollow projection 31 engaging the recess or channel portion of the side member of frame 1 and having an inwardly extending rib or lug 32. The outer ends of the brackets are provided with holes 34, which are engaged by studs 35, which constitute the pivots of hooks 33, the outer ends of which are adapted to engage the horizontal members of the supporting frames 22 and hold the latter and the upper mold sections therein in retracted position, during the operation of drying the casting and reconditioning the mold parts in the special drying rooms or compart-

125 130

ments of the pottery. The rear ends of the hooks engage the lug or detent 32, so that, when the frames 22 are swung upward, they lift the hooks and are ultimately caught 5 behind the latter. To release the frames 22 to permit the latter to be moved downward, it is necessary only to lift the individual hooks.

It will be particularly noted that the apparatus, as described, involves relatively few and simple parts, which are made either of standard stock forms of commercial iron or steel or of relatively rough castings, which require but a minimum of machining 10 or finishing, and the mold sections being of usual standard forms and materials, the entire apparatus involving the supporting truck and eight complete molds and their accessories may be made, assembled and adjusted in a minimum of time, labor and expense, but will afford an efficient means for effecting the casting of pottery ware of the character indicated under conditions which will insure a minimum loss of ware due to 15 the difficulties and defects inherent in the manual operations heretofore exclusively employed in fabricating relatively heavy pieces of pottery ware by casting the same from slip. The mold sections, when properly matched, assembled and adjusted on the trucks, are left in situ until they are worn out or so far damaged as to prevent further use, so that each truck constitutes a complete installation in which all of the 20 preliminary operations incident to the fabrication of ware of this character, are performed, said operations including the pouring of the slip into the molds, the preliminary drying of the castings to permit the upper or core section of the mold to be withdrawn, the secondary drying of the 25 castings while the latter are supported in the lower mold sections, the reconditioning of the mold sections as to humidity, and the final dumping of the castings from the lower mold sections.

In carrying out these operations, the portions of the upper mold sections, which engage the lower mold sections, are dusted 30 and each of the upper mold sections is swung down into registry with the mating lower mold section, after releasing the hooks 33. The two mold sections are then securely locked together by swinging the hooks 35 on the lower mold sections over the shafts 24 of the upper mold sections, as illustrated in dotted lines in the lower portion of Fig. 1. When the respective molds have been thus assembled and locked together and the 40 truck brought to the pouring station, the individual molds are charged with slip, in the manner disclosed in my copending application Serial No. 749,490, filed of even date herewith, the slip being delivered to 45 the individual molds by a flexible hose con-

nected with supply piping to an overhead tank containing the properly conditioned slip. The forward and downward inclination of the molds causes the slip to completely fill the entire mold cavity, as will be understood. After the pouring operation has been completed, the truck containing the filled molds is moved to a section of the pottery or factory where the air is conditioned as to temperature and humidity to 50 effect a preliminary drying of the castings in the closed molds, which will permit of the upper mold sections being separated and swung upward and backward to the retracted position illustrated in Fig. 1. This operation is facilitated by the particular means for mounting the upper mold section. The workman engages the horizontal member of frame 2 and lifts the frame with a jogging motion, through a slight distance, which has the effect of causing the detent 26 to strike the under face of the forward edge of the upper mold section slight taps or blows sufficient to jar the upper mold section loose 55 from the casting. After the upper sections of the molds have been withdrawn, they are immediately dusted, while they are still quite wet from the moisture absorbed from the casting. The trucks are then moved to a secondary drying and conditioning room or section, where the atmosphere is regulated as to heat and moisture content to effect such drying of the castings, without danger of impairment of the latter and, when this secondary drying has been accomplished, the trucks are then moved to the dumping position where the partially dried castings are removed from the lower mold sections. The dumping operation is performed by swinging the lower mold section on its journals 17 until the mold section is inclined forwardly from the vertical, when, as a general rule, the casting will drop out of the mold into the hand of the operator, but should the casting tend to stick to the mold section, the latter is revolved still further until the lugs 13 on the forward portion of the mold section supporting frame come into contact with the lower edge of the brackets 3, as illustrated in the upper part of Fig. 2. The impact of the lugs 13 against the bracket will jar the casting loose and permit the same to be readily removed from the mold.

Inasmuch as the mold sections have been properly conditioned as to humidity or moisture content in the secondary drying section, the truck, after the dumping operation has been effected, may be run back immediately to the casting station where the separated mold sections are again brought into registry and the casting and sequential operations repeated in proper order.

What I claim is:

1. Apparatus for casting pottery ware

- from slip comprising a portable support, a mold section pivoted thereon for rotary movement from charging to dumping position, a frame pivoted to said support above the mold section, and a second mold section pivoted in said frame and adapted to be swung into and out of engagement with the first mold section by the movement of said frame.
- 10 2. Apparatus for casting pottery ware from slip comprising a portable support, a mold section pivoted thereon for rotary movement from charging to dumping position, a frame pivoted to said support above the mold section, a second mold section pivoted in said frame and adapted to be swung into and out of engagement with the first mold section by the movement of said frame, and means for locking the mold sections in engaging relation.
- 15 3. Apparatus for casting pottery ware from slip comprising a portable support, a mold section pivoted thereon for rotary movement from charging to dumping position, a frame pivoted to said support above the mold section, a second mold section pivoted in said frame and adapted to be swung into and out of engagement with the first mold section by the movement of said frame, and means for adjusting the pivot support of the first mold section to secure registry of the two sections.
- 20 4. Apparatus for casting pottery ware from slip comprising a portable support, a mold section journalled on a horizontal axis on said support, a frame pivoted on said support above said mold section, a second mold section journalled on a horizontal axis in said frame, a detent on the frame for limiting the movement of the second mold section relatively to the frame, and means for effecting relative adjustment of the axes of rotation of the mold sections to effect proper registry of the sections.
- 25 5. Apparatus for casting pottery ware from slip comprising a truck, a lower mold section pivoted on a horizontal axis on said truck, a frame pivoted to said truck above the mold section, an upper mold section mounted on a horizontal axis in said frame and adapted to be swung into and out of engagement with the lower mold section by the movement of said frame, means for locking the mold sections in engaging relation, and means for locking the frame and upper section in retracted position.
- 30 6. Apparatus for casting pottery ware from slip comprising a truck, a lower mold section pivoted on a horizontal axis on said truck, a frame pivoted to said truck above the mold section, an upper mold section mounted on a horizontal axis in said frame and adapted to be swung into and out of engagement with the lower mold section by the movement of said frame, means for locking the mold sections in engaging relation, means for locking the frame and upper section in retracted position, and means for adjusting the axis of the lower mold to effect accurate registry of the mold sections.
- 35 7. Apparatus for casting pottery ware from slip comprising a truck including a rectangular frame having a wheeled suspension from an overhead trackway, horizontal brackets on the side bars of said frame having journal bearings thereon, a lower mold section journalled in said bearings, stops on said mold section to engage the brackets to limit the rotation of the mold section in one direction and hold the section inclined to the horizontal in pouring position, a secondary frame pivoted to the side members of the main frame above the brackets aforesaid, an upper mold section pivoted on a horizontal axis in said secondary frame and adapted to be swung into and out of engagement with the lower mold section by the movement of said frame, means for locking the mold sections together, and means for locking the secondary frame and upper mold section in retracted position.
- 40 8. Apparatus for casting pottery ware from slip comprising a truck including a rectangular frame having a wheeled suspension from an overhead trackway, horizontal brackets on the side bars of said frame having journal bearings thereon, a lower mold section journalled in said bearings, stops on said mold section to engage the brackets to limit the rotation of the mold section in one direction and hold the section inclined to the horizontal in pouring position, a secondary frame pivoted to the side members of the main frame above the brackets aforesaid, an upper mold section pivoted on a horizontal axis in said secondary frame and adapted to be swung into and out of engagement with the lower mold section by the movement of said frame, hooks carried by the lower mold section to engage the pivot means of the upper mold section to lock the sections together, and a hook on the main frame to hold the secondary frame and upper mold in retracted position.
- 45 9. Apparatus for casting pottery ware from slip comprising a truck including a rectangular frame having a wheeled suspension from an overhead trackway, horizontal brackets on the side bars of said frame having journal bearings thereon, a lower mold section journalled in said bearings, set screws in said bearings to adjust the position of the mold journals, stops on said mold section to engage the brackets to limit the rotation of the mold section in one direction and hold the section inclined to the horizontal in pouring position, a secondary frame pivoted to the side members of the main frame above the brackets aforesaid, and means for locking the mold sections together.

said, an upper mold section pivoted on a horizontal axis in said secondary frame and adapted to be swung into and out of engagement with the lower mold section by

5 the movement of said frame, means for locking the mold sections together, and means for locking the secondary frame and upper mold section in retracted position.

10. Apparatus for casting pottery ware from slip comprising a truck including a rectangular frame having a wheeled suspension from an overhead trackway, horizontal brackets on the side bars of said frame having journal bearings thereon, a 15 lower mold section, a clamping frame for said section having journals thereon engaging the bearings in said brackets, set screws passing laterally into said bearings to adjust the journals, a secondary frame 20 pivoted to the side members of the main frame above the brackets aforesaid, an upper mold section, a rod passing through said upper mold and journalled in the secondary frame, means for locking the mold 25 sections together, and means for locking the secondary frame and upper mold section in retracted position.

11. Apparatus for casting pottery ware from slip comprising a truck including a 30 rectangular frame having a wheeled suspension from an overhead trackway, horizontal brackets on the side bars of said frame having journal bearings thereon, a lower mold section, a clamping frame for 35 said section having journals thereon engaging the bearings in said brackets, set screws passing laterally into said bearings to adjust the journals, a secondary frame pivoted to the side members of the main frame 40 above the brackets aforesaid, an upper mold section, a rod passing through said upper mold and journalled in the secondary frame, a lug on the secondary frame engaging the inner face of the upper mold section to permit relative movement of said section and 45

frame in one direction, means for locking the mold sections together, and means for locking the secondary frame and upper mold in retracted position.

12. Apparatus for casting pottery ware 50 from slip comprising a rectangular vertical frame, a series of pairs of mold sections mounted on opposite sides of said frame, each pair comprising horizontally pivoted sections adapted to be swung into and out 55 of registry with each other, means for locking the sections of each pair together and means for locking one of the sections in retracted position.

13. Apparatus for casting pottery ware 60 from slip comprising a rectangular vertical frame, a series of pairs of mold sections mounted on opposite sides of said frame, each pair comprising horizontally pivoted sections adapted to be swung into and out 65 of registry with each other, means for adjusting one of the sections on its pivotal supports to insure registry with the other section, means for locking the sections of each pair together, and means for locking 70 one of the sections in retracted position.

14. Apparatus for casting pottery ware from slip comprising a rectangular vertical frame having wheeled suspension means attached to its top to engage an overhead 75 trackway, horizontal brackets extending laterally from the vertical members of the frame, lower mold sections adjustably journalled in said brackets on each side of the frame, auxiliary frames pivoted between 80 the vertical members of the main frame, complementary mold sections pivoted horizontally in said auxiliary frames, means for locking the sections of each pair together, and means for locking the auxiliary frames 85 and the mold sections carried thereby in retracted position.

In testimony whereof I affix my signature.

EDWARD S. LEA.
